UNITED STATES PATENT OFFICE.

WILLIAM EVERE, OF BUFFALO, NEW YORK.

SEWING MACHINE.

1,407,849.

Specification of Letters Patent. Patented Feb. 28, 1922.

Application filed April 24, 1919, Serial No. 292,243. Renewed November 18, 1921. Serial No. 516,249.

To all whom it may concern:

Be it known that I, WILLIAM EVERE, a citizen of the United States, residing at Buffalo, in the county of Erie and State of New York, have invented new and useful Improvements in Sewing Machines, of which the following is a specification.

This invention relates to the class of sewing machines which are employed principally by shoe repairers and which are especially useful for mending cuts and for button-holing.

In such machines, as hitherto constructed, the feeding foot in addition to its automatic backward and forward motion is capable of being turned by hand alternately in opposite or different directions to produce zig-zag stitches across cuts in a shoe, or along the edges of button holes, the foot being turned to a position diagonally of the cut or button hole, in order to feed or advance the work as well as shift it laterally to produce the zig-zag stitches.

This hand operation of the feeding foot is comparatively slow and tedious and requires special care and attention to produce uniform stitching.

It is the principal object of my invention to effect the turning or oscillating motion of the feeding foot by automatic means of simple and reliable construction, in order to increase the capacity of the machine and insure neat and uniform work.

A further object is the provision of convenient means for adjusting the foot-turning mechanism to produce coarse or fine stitching, as desired.

In the accompanying drawings: Figure 1 is a fragmentary, sectional side elevation of 40 a sewing machine embodying the invention. Figure 2 is a vertical longitudinal section on line 2—2, Fig. 5. Figure 3 is a similar section on line 3—3, Fig. 5. Figure 4 is a vertical section of the lower portion of the arm-head at right angles to Fig. 1. Figure 5 is a sectional top plan view. Figures 6 and 7 are side elevations of the feeding-foot and adjacent parts, showing different positions of the foot. Figure 8 is a horizontal section on line 8—8, Fig. 6. Figure 9 is a similar section on line 9—9, Fig. 7. Figures 10 and 11 are horizontal sections similar to Figs. 8 and 9, showing the use of the machine for button holing. Figure 12 is a transverse section on line 12—12, Fig. 1, with some of the

parts in a different position. Figure 13 is a fragmentary rear view of the machine. Figure 14 is a side elevation of the arm-head, partly in section. Figure 15 is a sectional elevation of parts of the foot-reversing mechanism.

Similar characters of reference indicate corresponding parts throughout the several views.

15 indicates the usual hollow arm of the machine having a suitable base, not shown, and 16 is the horizontal shaft journaled in the arm and provided at its projecting end with the customary hand and balance wheel 17, and the band-pulleys 18 for driving said shaft, in a well known manner.

19 indicates the needle-bar guided in the usual oscillating sleeve or bushing 20 journaled in the arm-head 21, the bar being actuated by the customary lever 22.

Arranged in the longitudinal groove 23 of said sleeve is the bar 24 which carries the feeding-foot 25. This bar is jointed at its upper end to the usual oscillating collar or bearing 26 which surrounds the needle-bar 19 and is carried by the cross head 28. As shown in Figs. 5 and 14, this cross-head has the usual vertically-sliding rod 29 guided in the arm-head and held in its depressed position by the spring 30 which engages a notched wing or plate 31 projecting from said rod. The parts just mentioned, including the feeding foot, are raised by the customary cam-lever 32 which engages the lower end of said wing.

The usual mechanism is shown in the drawings for producing the ordinary backward and forward feed motion of the foot 25. This mechanism comprises a vertically-movable ring 33 arranged horizontally below the arm-head and carried by an upright slide-bar 34 guided in said head and reciprocated by a grooved cam 35 secured to the shaft 16 and engaging a stud or roller 36 carried by said bar. Said ring is provided in its inner side with the annular groove 37 which receives the upper arm of a bell crank lever 38. As shown in Fig. 4, the divided pivot 39 of this lever is carried by ears 40 depending from a plate 41 secured to the lower end of the sleeve 20. The bifurcated lower arm of this bell crank lever is coupled to the bar of the feed-foot by the customary loop 42. By this construction when the shaft 16 is rotated, the grooved

ring 33 is reciprocated vertically, vibrating said bell crank lever and the feeding foot, in a well known manner.

In addition to the hand lever 32 for lifting the feeding-foot, suitable automatic means are provided for intermittently raising it. These devices preferably consist of an arm 43 secured to the shaft 16 and having a stud or roller 44 arranged to engage a lifting lever 45 pivoted in the head of the arm 15. The free end of this lever engages under a vertically-swinging lever or finger 46, which in turn is arranged to engage a lug 47 secured to the adjacent portion of the spring 30, whereby the lever 45 is raised, causing the feeding-foot to be elevated through the lever 46, spring 30 and slide rod 29.

The bar of the feeding-foot, being fitted in the groove of the oscillating sleeve 20, is compelled to rock or turn therewith, to change the position of the foot relatively to the cut to be mended or the button-hole to be reinforced. Such oscillation of the sleeve is effected automatically, preferably by the mechanism shown in the drawings, which is constructed as follows:

48 indicates a gear wheel or segment secured to the upper end of said sleeve 20, 30 and 49 a horizontally-sliding rack bar engaging said wheel and movable in suitable guides 50 and 51. This rack-bar is reciprocated from the shaft 16 by a grooved cam 52 secured to said shaft and operating a horizontal slide 53, a lever 54 actuated by said slide, and a link 55 connecting said lever with the rack bar. The slide 53 carries an oscillating head or button 56 having tenons 57 which engage the grooves of the cam 52, 35 this rocking capacity of the tenons being necessary to permit them to follow the curves of the cam groove. The slide 53 is provided at its front end with a downwardly-extending arm 58 carrying a vertically adjustable stud 59 which engages a substantially longitudinal slot 60 in the lever 54. The slide 53 is preferably guided in a plate 53^a removably secured to the arm 15, and the lever 54 is fulcrumed at 61 to an arm or bracket 50 53^b of said plate. By the above adjustment, the throw of said lever and the extent of oscillation of the feeding-foot, may be regulated, as desired. To afford a further range of adjustment for this purpose, the lever 54 55 is provided in its upper end with a longitudinal slot 62 for receiving the pin 63, which connects said lever with the link 55.

The operation of the machine is as follows:

60 Assuming that a cut or slit in a shoe is to be mended, the feeding-foot is lifted and the shoe is passed over the horn in the usual way, with the cut located at one side of the needle. Upon lowering the feeding-foot 65 and operating the machine, the work is auto-

matically fed past the needle in a zig zag course, producing stitches of that form across the cut, as shown in Figs. 8 and 9. To effect this compound forward and lateral movement of the work, the feeding-foot 70 must be so placed or adjusted as to stand diagonally of the cut at both extremes of its oscillatory movement, as shown in the figures just referred to. The angle of these diagonal positions may be increased or diminished by the adjustable connections between the rack bar 49 and the slide 53, hereinbefore described, and this variation in angle determines the fineness or coarseness of the stitches. 75

To prevent displacement or twisting of the work, the feeding-foot must be automatically lifted wholly clear thereof before beginning its reversing movement, and the foot must also be held out of contact with the work until it has been fully turned back to the opposite extremity of its oscillating movement. As shown, the portions of the lifting lever 45 engaged by the stud 44 are properly shaped for this purpose. 80

This automatic turning or reversing action of the feeding-foot not only expedites the work and increases the capacity of the machine, but produces a more uniform and neater stitch than can be obtained by effecting such reversing action by hand. 90

While the machine is especially serviceable for shoe-repairing, it is equally useful for button holing, this use being illustrated in Figs. 10 and 11. 100

To facilitate the angular adjustment of the oscillating feeding-foot, one end of the link 55 is preferably detachable from the adjoining members of the foot-turning mechanism. In its preferred construction, the rear end of the link is provided with a notch 64 which engages the end bolt 63, as shown in Fig. 15. Upon disconnecting the link from this lever, the rack bar 49 may be moved by hand to turn the gear wheel 48 110 and the feeding-foot controlled by it, to the desired angular position, after which the link is re-engaged with said lever.

To enable the machine to be used for ordinary stitching, other than zig-zag, say along the curved edge of a patch, the sleeve 20 is preferably provided with the usual handles 65 for turning it manually. The detachable connection 55 permits the automatic foot-oscillating mechanism to be 120 thrown out of action during such hand operation.

I claim as my invention:

1. In a machine of the character described, the combination of an oscillatory feeding-foot, means for vibrating the foot, and automatic means for changing the angular position of the foot after each feed stroke to produce a zig-zag stitch. 125

2. In a machine of the character described, 130

the combination of an oscillatory feeding-foot, means for vibrating the foot, automatic means for changing the angular position of the foot after each feed-stroke to 5 produce zig-zag stitches, and means for automatically lifting the foot clear of the work before each reversal thereof.

3. In a machine of the character described, the combination of an oscillatory feeding-foot, means for vibrating the foot, and automatic means for oscillating the foot after 10 each feed stroke to produce zig-zag stitches, including a gear wheel and a rack bar engaging said wheel.

15 4. In a machine of the character described, the combination of an oscillatory feeding-foot, means for vibrating the foot, and automatic means for oscillating the foot after each feed stroke to produce zig-zag stitches 20 including a gear wheel, a rack bar engaging said wheel, a rotary shaft, and a cam on said shaft for reciprocating said rack bar.

5. In a machine of the character described, the combination of a feeding-foot, means for 25 vibrating the foot, an oscillatory member engaging said foot to cause it to turn therewith, a gear wheel connected to said oscillatory member, a rack bar engaging said wheel, a rotary shaft carrying a cam, and a 30 slide operated by said cam and connected with said rack bar.

6. In a machine of the character described, the combination of an oscillatory member, a feeding-foot connected to said member to turn therewith, means for vibrating the foot, 35 a gear wheel for actuating said oscillatory member, a rack bar engaging said wheel, a rotary shaft carrying a cam, a slide actuated by said cam, and an adjustable connection between said slide and said rack bar for 40 varying the throw of said oscillating member and the foot.

7. In a machine of the character described, the combination of an oscillatory feeding-foot, means for vibrating the foot, and automatic means for oscillating the foot including 45 an oscillatory wheel and a reciprocating member engaging said wheel, driving mechanism, and an adjustable connection between said reciprocating member and said 50 driving mechanism.

8. In a machine of the character described, the combination of an oscillatory feeding-foot, means for vibrating the foot, and automatic means for oscillating the foot after 55 each feed stroke to produce zig-zag stitches including a gear wheel, a rack bar engaging said wheel, driving mechanism and a link detachably connecting said rack bar with said driving mechanism.

WILLIAM EVERE.
